CONVEX PUTTING SURFACE

Fred W. Preece, Toledo, Ohio, assignor to Tri-Putt Company, Toledo, Ohio, a corporation of Delaware

Application April 12, 1940, Serial No. 329,309

2 Claims. (Cl. 273—35)

This invention relates to putting game structures and the particular novelty of this invention resides in the provision on the putting surface of a convex portion and the structure whereby this convex surface is obtained.

In games of this nature an inclined putting surface is provided which has an inclined bottom spaced therefrom and which has a plurality of openings therein so that a ball may be dropped therethrough to the bottom and be returned to a receptacle adjacent the platform at the front of the device provided for the putter. Heretofore in games of this nature, if a ball was struck and did not enter one of the openings provided therefor or was not struck hard enough to go beyond the end of the putting surface, the ball would be returned to the putting platform. By the provision of a convex portion in the putting surface forwardly of the openings provided therein, this difficulty is obviated since such portion will act to direct the ball to one side or other of the putting surface where it is trapped, dropped through an opening to the inclined bottom and returned to the receptacle.

To the accomplishment of the foregoing and related ends, said invention, then, consists of the means hereinafter fully described and particularly pointed out in the claims. The annexed drawing and following description set forth in detail certain mechanism for carrying out my invention, said means constituting however but one of various ways in which the principle of the invention may be used.

In said annexed drawing, wherein like reference numerals refer to like parts throughout the various views:

Fig. 1 is a plan view of my improved putting apparatus showing more particularly the location of the convex surface thereon.

Fig. 2 is a fragmentary vertical longitudinal section taken centrally through the device of Fig. 1, and

Fig. 3 is a vertical section taken substantially on the plane of line 3—3 of Fig. 2 looking in the direction indicated by the arrows.

The structure is provided with a frame having side members 1 having inclined upper edges 2 and a vertical back member 3. Above the frame at the rear of the device is usually located an indicating mechanism for indicating the score of a person putting but is not shown here since it forms no part of the present invention.

At the inner sides of the side members cleats 4 are located on an inclined plane substantially parallel to the upper edges 2 of the side members

and are secured thereto as particularly shown in Figs. 2 and 3. Immediately above the cleats 4 and secured to the upper edges thereof is located the bottom member 5. Spaced upwardly from the bottom and also secured to the inner sides of the side members 1 and substantially parallel to the lower cleats 4 are the upper cleats 6. At the forward end of the device these upper cleats are curved slightly and extend further outwardly in a horizontal plane as shown in Fig. 2 so that the platform 7 may be supported thereby.

Located above the bottom member 4 and spaced a distance therefrom is the top member 8 which is also on an incline and provides the putting surface which is covered with a suitable material. Elongated supporting members 9 are secured to the upper edges of the upper cleats 6 and the top member 8 is secured at its longitudinal edges to the supporting members 9.

Near the rear upper end of the putting surface 8 is located a plurality of openings 10 which will receive the ball and permit it to be dropped therethrough to the bottom 5 which, being considerably inclined, will carry the ball toward the front of the machine and into a receptacle provided for that purpose. The rear end of the putting surface is spaced from the rear of the frame providing the space 11 so that if a ball is putt beyond any of the openings 10 it will be received in the space 11 and conveyed along the bottom 5 to the receptacle at the front of the device. Near the rear end secured to the bottom 5 a plurality of partitions 12 are provided in alignment with the edges of the openings 10 so that a ball dropped in any one of the openings will be received in a corresponding space between two of the partitions 12. These partitions 12 extend only a short distance along the central portion of the bottom 5 sufficiently so that the score may be registered after the ball has dropped through one of the openings 10 after which it rolls along the bottom 5 and is returned to the receptacle.

A plurality of supporting members are provided above the partitions 12 which extend transversely of the device and are secured at their ends to the supporting members 9. Any number of these transverse members may be employed so long as the desired result is obtained, but in practice and in the preferred embodiment of my invention shown I prefer to use five of such members. The frontmost and rearmost of these members is indicated in Fig. 2 by the numeral 13; the next adjacent member to each of the members 13 is indicated by the numeral 14; and the central member is indicated

by the numeral 15. These members support the putting surface 8 and are located in the specific location shown so as to form the convex section in the putting surface. The members 14 and 15 have curved upper edges which have their greatest height at the longitudinal center thereof substantially as shown in Fig. 3, but the central member 15 is of a greater height at its center than the members 14. The members 13 are substantially flat along their upper edges and merely provide additional support for the putting surface.

The putting surface 8 is formed of thin material adapted to lie over these transverse supporting members and assume the contour thereof which will result in a convex surface both longitudinally and laterally of the putting surface at the location of these transverse members. Since the central member 15 is of greater height than the members 14, which are in turn of greater height than the member 13 the putting surface will have a longitudinal central configuration as shown in Fig. 2. Also, since the putting surface will adapt itself to the longitudinal configuration of the transverse supporting members, its lateral section will also be convex as shown in Fig. 3 to provide the resulting convex portion 16 as indicated in plan in Fig. 1.

To complete this portion of the structure, the additional supporting elements 17 at each side of the frame are located over the outer longitudinal edges of the putting surface 8 and support at their upper edges the transparent closure member 18, shown here as formed of glass to thereby prevent access to this portion of the structure.

Adjacent the frontmost edge of the convex portion 16 and at each side of the frame is a guide member 19 which has one end thereof secured to the sides of the frame and is then curved outwardly and rearwardly in the manner shown in Fig. 1. Adjacent the front portion of each of the guide members 19, is located an opening 20 to permit a ball which has been returned to that portion of the surface to drop through to the bottom 5 and be returned to the receptacle. It should also be noted here at the upper rear edge of the putting surface, are located the inclined members 21 which are inclined outwardly from the center thereof so that when a ball goes beyond the edge of the putting surface and is received in the space 11, there will be no possibility of such ball reaching one of the spaces between the partition 12 to indicate a score which was not rightfully obtained.

Beneath the putting surface 8 and adjacent one side of the frame, a guide board 22 is located which extends almost to the opposite side and is inclined downwardly as shown in dotted lines in Fig. 1. This member then continues forwardly as at 23 and is then curved to one side of the frame so that all balls whether reaching the bottom 5 by the space 11, the openings

10, or the openings 20 will be guided to the space between one of the side members 1 and the member 23 to thereby be returned to the receptacle. A receptacle is indicated generally at 24 but may 5 be of any desired form which may even include a machine to again dispense the balls.

From the foregoing it will be apparent that a ball having been putt from the platform 7 will be moved over the convex surface 16 to drop into one of the openings 10, if the ball is struck with sufficient force it may go beyond such openings and into the space 11, if, however, the ball does not enter either the opening 10 or the space 11, the convex surface 16 will carry it to one side or to the other of the frame where it will eventually be received in an opening 20 and carried back to the receptacle 24 by means of the inclined bottom 5.

Other modes of applying the principle of my invention may be employed instead of the one here disclosed, change being made as regards the mechanism herein shown, provided however that the means stated by any of the following claims or the equivalent of such stated means be employed.

I claim:

1. A putting game structure comprising, an inclined frame having side members along the length thereof, lower inclined cleats secured to the inner sides of said side members, a bottom member secured to and supported by said cleats, upper inclined cleats secured to the inner sides of said side members spaced from and substantially parallel to said lower cleats, elongated supporting elements secured to the upper sides of the upper cleats, a plurality of spaced apart supporting members extending transversely of said frame and secured at their ends to said elongated supporting elements, some of said 30 transverse members having curved upper sides and being of greater height in the center than on the ends thereof, and a covering therefor supported at its longitudinal side edges on said elongated supporting elements following the contour 35 of said transverse supporting elements, to thereby provide a convex putting surface.

2. A putting game structure comprising, a frame having side members, an inclined bottom member extending between said side members, elongated supporting elements spaced from and parallel to said bottom and secured to the inner side of each side member, a plurality of spaced apart transverse supporting members secured at their ends to said elongated supporting elements, 40 some of said transverse members having curved upper edges and being of greater height in the center than on the ends thereof, and a covering therefor supported at its longitudinal side edges on said elongated supporting elements following the contour of said transverse supporting elements, to thereby provide a convex putting surface.

FRED W. PREECE.
